UNITED STATES PATENT OFFICE.

EDWARD M. CARROLL, OF PORT TAMPA CITY, FLORIDA.

LOCOMOTIVE ARCH-BRICK.

1,275,386.

Specification of Letters Patent. Patented Aug. 13, 1918.

Application filed October 8, 1917. Serial No. 195,388.

To all whom it may concern:

Be it known that I, EDWARD M. CARROLL, a citizen of the United States, residing at Port Tampa City, in the county of Hillsborough and State of Florida, have invented certain new and useful Improvements in Locomotive Arch-Bricks, of which the following is a specification.

This invention relates specifically to a form of brick especially adapted to be used in a locomotive boiler furnace and generally to a septum wall composed of the brick, and it consists in the novel features hereinafter described and claimed.

15 A primary object of the invention is to provide a brick of especial design and configuration whereby it may be used at the intermediate or side rows in the wall structure and whose function is, by reason of the 20 disposition and arrangement of its surfaces and features, to eliminate the necessity of having to clean the arches of the wall, to save fuel, to protect the crown sheet of the fire box, to prevent accumulation in the 25 boiler flues, and to protect the lower boiler flues from intense heat by effecting a uniform distribution of the heat to all of the flues, high and low.

With these and other objects in view the 30 brick comprises a body which is rectangular in top plan, whereby one brick may fit squarely against the adjacent bricks in the wall structure thus providing a continuous wall in so far as contact is concerned. But 35 the bricks are so shaped that while they form several rows of arches in the wall structure, there are interstices or openings between each individual brick and the adjacent bricks through which the heat may 40 pass in relatively fine streams or volumes thereby dividing the entire volume of the gas and effecting the uniform distribution of the heat to the boiler flues as above referred to. This is accomplished at the side 45 portions as well as at the intermediate portions of the septum or arch wall and hence the bricks used at all portions of the wall are of the same dimensions, arrangement and configuration.

50 The body of each brick is provided at its under side with a concaved surface which extends longitudinally of the body. The upper surface of the body is convexed and these surfaces are disposed at an acute an-

gle with relation to each other whereby the 55 body is thicker at one end than at the other. At its thicker end and under side and between its side edges the body is chamfered thereby providing the heat passageway above alluded to, and the body is provided 60 at its thicker end and side portions with recesses which communicate at their inner ends with the chamfered portion and serve to divide and lead the heat over the supports upon which the brick is mounted. 65 The body is further provided along its longitudinal side edges with grooves adapted to receive the supports whereby the bricks in one row of the wall structure may have direct contact with the bricks in the adjacent rows thereby binding all of the 70 bricks along their entire perimeter in the wall structure and preventing one or more bricks from being dislodged from the same and opening a gap.

75 In the accompanying drawings—

Figure 1 is a longitudinal sectional view of a locomotive boiler furnace showing the brick in position therein.

Fig. 2 is a fragmentary transverse sectional view of the same.

Fig. 3 is an enlarged fragmentary plan view of the arch wall and supports.

Fig. 4 is a sectional view taken on the line 4—4 of Fig. 3.

Fig. 5 is an end view of a brick showing the supports in section.

Fig. 6 is a similar view looking at the other end of the brick.

Fig. 7 is a perspective view of one of the 90 bricks.

As illustrated in Fig. 1 of the drawing the locomotive boiler 1 is provided with the usual furnace or fire box 2. Fire tubes or flues 3, are connected with the inner side of 95 the furnace and extend along the boiler 1 in the usual manner. The furnace is provided at its front side with a fuel inlet opening 4, which also passes through the front of the boiler. Water tubes 5 are located in 100 spaced relation in the furnace 2 and pass through the front and rear sides thereof so that water from the boiler 1 may pass freely around the said tubes and traverse the length of the furnace. The tubes 5 are parallel with 105 each other and are inclined downwardly and forwardly. Their rear ends are connected with the end sheet of the furnace at points

above the upper edge of the opening 4 and their forward ends are connected with the opposite sheet of the furnace at points below the lower edge of the opening 4 and 5 below the flues 3.

A grate 6 is located in the lower portion of the furnace 2. These parts and their arrangement are conventional, hence further description in this respect is unnecessary.

- 10 The septum wall which is composed of the bricks, to be described, is mounted on the tubes 5 as shown in Fig. 1 of the drawing, wherein it will be seen that the said wall is in an inclined position and extends from the 15 inner sheet of the furnace 2 to a line which is located at a level above the level at which the upper edge of the opening 4 lies. Therefore, when fuel is thrown into the furnace through the opening 4 it is deflected by the 20 septum wall down toward the grate 6 and particles of the fuel cannot pass directly into the flues 3 and choke the same. Thus a saving of the fuel is effected as all of it deposits upon the grate for consumption and 25 the flues are kept free from accumulation of particles of the fuel.

The septum wall is composed of bricks of especial design and configuration and as all of these bricks are of identical dimensions, 30 pattern and shape a description of one will suffice.

Each brick includes a body 7 of clay or other suitable material. The body is provided at its under side with a concaved surface 8 disposed longitudinally thereof. At 35 its upper side the said body is provided with a convexed surface 9 also disposed longitudinally thereof. The surfaces 8 and 9 are disposed at an acute angle to each other longitudinally of the body, consequently the body is thicker transversely at one end than at the other. The body is rectangular in shape in top plan. At its upper side the body is provided with a hollow 10, which reduces the 40 material and weight of the body. At its thicker end and between its side edge portions the body 7 is chamfered as at 11. This 45 chamfered surface or cavity leads in from the end of the block and terminates at an edge located between the ends of the concaved surface 8.

Recesses 12 are provided at the thicker end of the body 7 and the said recesses lead in from the side edges of the body and communicate at their inner ends with the chamfered cavity 11 at points between the surfaces 8 and 9 of the body and spaced therefrom.

The body 7 is further provided at its side 60 edge portions with grooves 13 which traverse the length of the body.

When the bricks are assembled in the form of a septum wall on the tubes 5, the said tubes are received in the grooves 13 whereby 65 the edges of the bricks in the adjacent rows

of bricks come in direct contact with each other as best shown in Figs. 2 and 3 of the drawing. In each row of the bricks the thinner end of one brick is in direct contact with the thicker end of the next adjacent brick so that the upper ends of the chamfered cavities 11 are left open and unobstructed as best shown in Fig. 4. Hence all of the bricks are confined along all of their edges and securely held in position in 75 the wall structure.

As the gas ascends from the grate and strikes the septum wall it passes through the chamfered cavities 11 and is thereby separated into relatively small streams or volumes by the bricks of the wall and thus separated pass to and through the flues 3. This effects a uniform distribution of the heat among the flues and does not subject the lower flues to a hotter blast than that supplied to the upper flues. Hence one set of flues will not burn out or spring leaks earlier than any other set, as a consequence of non-uniformity of the heating.

By reason of the shape of the bodies of the bricks, each row of bricks is in the form of an arch as shown in Fig. 2 and these arches extend longitudinally of the furnace and serve to retain the heat against the lower portions of the tubes thus facilitating the 90 heating of the water in the same and the 95 production of steam in the boiler.

By reason of the specific configuration of the bodies of the bricks, they may be arranged with the ends of the arches of the 100 same level or at different levels as shown in Fig. 2 and as desired. The recesses 12 serve as passageways for conducting the heat from the chamfered cavities 11 and hence additionally separate or split the volumes or 105 streams of gas which emerge from the cavities before passing to the fire tubes or flues 3. These also materially assist in diffusing the heat over the crown sheet of the furnace and boiler thereby preventing warpage and 110 leakage at the joints of the same.

Having described the invention, what I claim as new and desire to secure by Letters Patent is:—

1. A brick comprising a body provided at 115 its under side with a concaved surface and at its upper side with a convexed surface, said surfaces being disposed at an acute angle with relation to each other longitudinally of the body, the under portion of the 120 body being chamfered at one end, and the upper convexed surface having a depression formed therein.

2. A brick comprising a body provided at 125 its under side with a concaved surface and at its upper side with a convexed surface, said surfaces being disposed at an acute angle with relation to each other longitudinally of the body, the under portion of the 130 body being chamfered at one end, the body

being further provided at its edge portions with recesses which communicate with the chamfered portion.

3. A brick comprising a body provided at its under side with a concaved surface and at its upper side with a convexed surface, said surfaces being disposed at an acute angle with relation to each other longitudinally of the body, the under portion of the body being chamfered at its thicker end, the body being further provided at its edge portions with recesses which communicate with the chamfered portion.

4. A brick comprising a body provided at its under side with a concaved surface and at its upper side with a convexed surface, said surfaces being disposed at an acute angle with relation to each other longitudinally of the body, the under portion of the

body being chamfered at one end and between its side edges, the body being further provided at its edge portions with recesses which communicate with the chamfered portion. 20

5. A brick comprising a body provided at its under side with a concaved surface and at its upper side with a convexed surface, said surfaces being disposed at an acute angle with relation to each other longitudinally of the body, the under portion of the body being chamfered at one end and between its side edges, the body being further provided at its edge portions with recesses which communicate with the chamfered portion and provided at its side edges with longitudinally disposed grooves. 30 35

In testimony whereof I affix my signature.
EDWARD M. CARROLL.
